CROSSBAR SELECTOR SWITCHING UNIT

Charles Gillings and Lawrence John Murray, Liverpool, England, assignors to Automatic Electric Laboratories, Inc., Chicago, Ill., a corporation of Delaware

Application December 4, 1943, Serial No. 512,888
In Great Britain January 8, 1943

8 Claims. (Cl. 179—22)

1

The present invention relates to switching equipment for use in telephone and like systems, and is more particularly concerned with selecting switches of the cross-bar type having sets of contacts arranged to form both rows and columns at right angles to one another.

In our application Serial No. 513,370, filed December 18, 1943, we have described a crossbar switching system in which each of a number of switching stages is controlled by equipment individual to each stage and the object of the present invention is to provide a crossbar selector having improved arrangements for outlet testing whereby the amount of apparatus in the individual control equipment is reduced.

On, say, a 200-point crossbar group selector having ten levels and twenty outlets per level there will be provided ten horizontal bar level-selecting relays and twenty vertical bar holding relays whereby connection may be made via the crossbar switch contact springs with any one of the two hundred outlets.

In the above-mentioned application, testing over a group selector level of twenty outgoing links to subsequent selectors was performed by testing directly from the common control group on to the associated outgoing P conductors, there being provided in the control group one or more hunter uniselectors together having ten levels with twenty outlets per level, the particular level involved being selected by a digit receiving switch in accordance with the particular group selecting digit dialled.

According to the invention a crossbar selector switching unit has control equipment associated with it which equipment comprises a selector adapted to connect with and test a number of leads corresponding to the number of lines in a group each of said leads being connected to corresponding leads of the group required by elements of the crossbar switching unit itself such elements being selected in accordance with the number of impulses by which the operation of the unit is initially controlled.

Conveniently the control equipment is individual to the unit which it controls although it will be appreciated that circumstances may make it desirable for a single unit to control more than one crossbar selector switching unit.

The invention will be better understood from the following description of one method of carrying it into effect, reference being had to the accompanying drawings comprising Figs. 1-5.

Figs. 1-4 when arranged in the manner indicated in Fig. 4a show circuits of a 200-point

2

crossbar group selector and associated common equipment which is assumed to be located in the first numerical group selecting stage of an automatic telephone system such as is described in the above-mentioned application. Fig. 5, which is located on the same sheet as Fig. 4, shows the group selector trunking diagram.

For convenience the designations in the present circuits have been made to line up as far as is possible with those of the circuits in the prior application and the group selector shown is therefore assumed to be designated GSU1, while its associated common group is designated GCG.

In the circuits the number of contact units carried by each relay is shown beneath its designation, as for instance

B
9

20 (Fig. 3) and these are designated individually in small letters which in this instance will be *b*1, *b*2, etc. A slow-to-release relay is shown with a hatched portion at one end of the rectangle indicative thereof, while a slow-to-operate relay is shown with a cross at one end, such a relay being in some instances slow-to-release as well as slow-to-operate.

As regards the crossbar vertical and horizontal relays, these are each indicated by a hatched rectangle, the contact units individual thereto being indicated in the same manner as for ordinary relays. The sets of crossbar switch contacts proper which are closed at the intersection of any given pair of horizontal and vertical bars, for instance the contacts controlled by relays 1GSP (Fig. 1) and 1GSH (Fig. 2), are designated

1GSP, 1GSP,
1GSH, 1GSH

40 and so on for each set of contacts involved.

Of the various uni-selectors such as the control group hunter switch which is designated OCS, the various sets of wipers and banks are designated OCS1, OCS2, etc. The driving magnet which is indicated by a hatched square will in this instance be designated OCM, and the magnet interrupter contacts will be designated ocm. In the case of the digit switch uniselector TDS, since the number of positions required is considerably less than the twenty-five available they are arranged to make two appearances thereon so that this switch will have two home positions 1 and 12.

Referring now to Fig. 5, the group selector comprises two crossbar switching units with their

vertical bars in effect coupled together as shown to form a group selecting unit. More specifically, the coupling will be effected electrically by the connection of each column of vertically commoned contact springs of the spring sets in one unit with a corresponding column of vertically commoned contact springs on the other unit of the pair.

The selector is of the 10-level 20-outlet-per-level type and is capable of handling ten connections, and for this purpose the ten incoming links will connect with the horizontal bar relays 1GSP—10GSP. The horizontal bars provided for the purpose of determining the selected one of the ten possible levels are controlled by the relays 1GTP—10GTP and the two sets of 20 vertical holding relays 1GSH—20GSH and 1GTH—20GTH when operated in pairs such as 1GSH and 1GTH or 2GSH and 2GTH, and so on, and in conjunction with one incoming and one level selecting relay, enable the two units of the pair forming the group selector switch proper to function to connect an incoming external link via a free internal link within the selector to a free one of the twenty outgoing links accessible from a selected level of the selector.

Referring now to the circuits of Figs. 1-4, circuits of the group selector GSU1 are shown in the upper parts of Figs. 1 and 2, while circuits of the control group GCG are shown in the lower parts of these figures and in Figs. 3 and 4.

In the group selector circuit there is shown only the horizontal prepare relay 1GSP together with the auxiliary relays 1GSR and 1NF associated with the first out of the ten possible incoming internal links to the selector, which relays, in common with the corresponding relays of the nine other incoming links have access over common leads 31—37 to group GCG. In addition, the vertical hold relays 1GSH and 1GTH of the first vertical internal link and the horizontal prepare relay 1GTP associated with the first of the ten possible outgoing levels are also shown which are operable from group GCG over leads 40—43.

The control group GCG comprises a set of relays and two uni-selectors of the 25-point reverse-drive electro-magnetically-operated type, the thousands dialled digit being received on switch TDS, whereupon one of the level selecting relays 1GTP—10GTP is operated in accordance with the digit dialled. All the vertical hold relays 1GTH—20GTH not already in use are thereupon operated, while the hunter switch OCS is set in operation and is caused to test over the selected outgoing level, connection between the contacts of switch OCS and the lines connected to this level being effected via the crossbar contacts at the intersection of the actuated level selecting horizontal bar and the vertical bars. When switch OCS finds a free outlet, the corresponding GSH relay is operated and this maintains a holding circuit for the relevant GTH relay on to the P conductor of the selected outlet when the control group is subsequently released and becomes available for piloting a further call through the same group selector.

When the group selector is taken into use, the calling subscriber's loop is extended on to the left-hand incoming negative and positive leads (Fig. 1), which leads will relate to the first of the ten possible incoming external links to the selector switch, and the terminating crossbar relay 1GSP will operate over the following circuit: earth, contacts 1gsr4, 1gsp5 and 1nf4, positive conductor, subscriber's loop, negative conductor,

5 contacts 1nf3, 1gsp4, and 1gsr3 to battery via the winding of relay 1GSP. This relay at contacts 1gsp4 and 1gsp5 extends the calling loop through via common leads 34 and 35 to relay A in the control group GCG and although at these contacts it disconnects its own operating circuit it remains locked via make-first contacts 1gsp1 and contacts 1nf5 to lead 36 which is earthed via contacts gsr1 of relay GS which will have been operated over the incoming P lead from the outlet testing relay in the preceding stage before the loop is extended forward to the group selector.

10 Relay A in operating at contacts a1 (Fig. 3) operates relay B in series with rectifier MRD in a conductive direction to battery via resistance YP. Relay B in operating, at contacts b1 (Fig. 1) extends earth over common lead 32 and then via contacts 1gsp2 to operate relay 1GSR in series with resistance YH, at contacts b2 brings up relay 15 BB (Fig. 3), while an alternative locking circuit for relay 1GSP (Fig. 1) is completed at contacts b4. At contacts b7 (Fig. 3) an energising circuit is completed for relay C on its series-connected windings in series with resistance YQ and switch magnet TDM (non-operative in this condition), while at contacts b8 relay B is locked up independently of the operated contacts a1. The group selector relay 1GSR in operating at contacts 20 1gsr1 extends the earthed lead 32 through to the incoming P lead and this earth extends back to hold the relays in the preceding stage which are connected to the P wire; contacts 1gsr1 also disconnect the operating circuit for relay GS which commences to release slowly. 30 At contacts 1gsr3 it prevents relay 1GSP from being re-connected to the incoming negative lead on any subsequent release of this latter relay, while at contacts 1gsr4 it prevents earth from being connected to the positive lead on the above condition. At contacts 1gsr5 the continued holding of relay 1GSP is rendered independent of contacts 1nf5. In the control group relay BB in operating at contacts b1 (Fig. 1) disconnects the relay GS from all the incoming P leads to the selector so as to mark the group selector as 35 busy. At contacts bb2 a dial tone source is connected up over lead DTE to the centre winding of relay A from whence it extends by induction into the outer windings and then on to the speaking leads and back to the calling party. Relay C in operating at contacts c2 (Fig. 3) prepares for the reception of the thousands dialled digit on to magnet TDM of the switch TDS from contacts 40 a1 of relay A (Fig. 1) which is operated from the calling loop.

45 The calling subscriber on hearing the dial tone should now proceed to dial the thousands digit of the required number, but in case he should neglect to dial and so hold common equipment GCG unnecessarily, arrangements are made to release this equipment and to return busy tone to the calling subscriber if dialling does not take place within a predetermined period after seizure. This is effected in the following manner by the 50 use of the pair of relays TA and TZ (Fig. 3) in conjunction with a delay set (not shown) which is common to the exchange and which is arranged to supply earth-pulses bearing a definite time relation to two common leads S and Z. On operation of relay B when the control group GCG is 55 taken in use, contacts b3 (Fig. 3) connect the right-hand winding of relay TA to the S lead and if or when the delay set is in its normal position an earth will be encountered on this lead and relay TA will operate. At contacts ta1 it locks to 60

earth on to the left-hand winding, at contacts ta_2 it connects its middle winding and the lower winding of relay TZ to the Z lead, while at contacts ta_3 it extends earth on to the delay set start lead ST. After the predetermined period an earth pulse is applied from the delay set to the Z lead, whereupon relay TZ operates and at contacts tz_3 removes the short-circuit from its upper winding over which it locks to the earthed contacts b_2 via resistance YJ. At contacts tz_1 and tz_2 the initial operating and locking circuits for relay TA are opened but this relay remains held in the circuit including its middle winding and the lower winding of relay TZ. At contacts tz_1 earth is extended over lead 33 to short-circuit and initiate the release of relay !GSR in the group selector, while at contacts tz_4 (Fig. 2) earth is extended over lead 37 to bring up relay !NF in the group selector. At the end of the Z pulse, relay TZ remains held and relay TA releases. In the group selector relay !NF in operating at contacts inf_1 maintains earth on the incoming P lead and disconnects any circuit therefrom to relay !GSR, while at contacts inf_2 a locking circuit is completed for relay !GSR but in this instance this circuit is ineffective owing to the short-circuiting over lead 33. At contacts inf_3 and inf_4 the incoming speaking leads are transferred from relay A to relay !NF, whereupon relay A releases. At contacts inf_6 number-unobtainable tone is, on release of relay !GSR, connected up over common lead NTE to the centre winding of relay !NF from whence it returns to the calling party; relay !GSR in releasing releases relay !GSP. In the control group, relay A in releasing at contacts a_1 short-circuits and releases relay B, whereupon relays BB and TZ are released, while the TDS switch is stepped off-normal on the release of relay C and is then homed as is described later and the control group GCG is then ready to handle a subsequent call through the group selector.

If the calling party commences to dial within the allowable predetermined period after receipt of dial tone, then on the first release of relay A an energising circuit is completed for magnet TDM as follows: earth, contacts b_8 , a_1 and c_2 , left-hand low resistance winding of relay C, magnet TDM to battery; the winding of relay B is short-circuited during this time, while the right-hand winding of relay C is similarly short-circuited in series with resistance YQ. On re-operation of relay A at the end of the first impulse of the dialled train, an energising circuit is re-completed for relay B and relay C now holds operated on both its windings in series with magnet TDM which will not hold in this condition and which thereupon releases to advance its wipers to contacts 2 or 13 according to which half of the banks is being used. An operating circuit is now completed for relay N via wiper and bank TDS!, operated contacts bb_3 and contacts n_2 to battery via resistance YO. This relay in operating, at its contacts n_1 opens the holding circuit for relay C and at the same time short-circuits its right-hand winding, at contact n_2 prepares for the operation of relay NR and at contacts n_3 (Fig. 1) disconnects the dial tone circuit.

Succeeding impulses of the train are delivered to magnet TDM and relays B and C hold operated during this time. It may be mentioned here that the presence of the metal rectifier MRD in the initial energising circuit for relay B serves to prevent the slowing up of the operation of the magnet TDM which would otherwise result from 75

the direct connection of a comparatively low value non-inductive resistance such as YP in parallel with its winding; neither magnet TDM nor relay C moreover will hold operated in series with relay B.

At the end of the digit, relay A remains operated and holds relay B, while relay C commences to release slowly. On release of relay C, contacts c_1 (Fig. 2) extend earth over operated contacts n_4 and b_9 and wiper TDS2 which will be in position 2 or 13 if say digit 1 has been dialled; whereupon the level 1 crossbar selecting relay !GTP will be operated to actuate the horizontal bar associated with the first one of the ten levels of outlets. Contacts c_3 complete an operating circuit for relay NR and this relay in operating at contacts nr_1 (Fig. 1) further disconnects any circuit to relay GS, and at contacts nr_2 (Fig. 3) completes a self-interrupted driving circuit for magnet OCM of switch OCS via bank and wiper OCS1, contacts kr_2 and kr_4 , magnet interrupter contacts ocm , magnet OCM to battery, the driving circuit being subsequently maintained by the low resistance winding of relay N. Contacts nr_3 (Fig. 2) extend earth over lead 43 which is common to all the relays !GTH—2GTH on the group selector, whereupon assuming that none of these relays are already in use, they will all be operated. Since the level 1 selecting relay !GTP is already operated, the sets of crossbar contacts on this level will be operated and will connect the control group GCG through to the P conductors of all twenty of the outgoing links on level 1 in the following manner. For instance, as regards relay !GTH shown, with this relay operated in addition to relay !GTP, then the set of contacts

1GTH
1GTP1—3

40 shown in Fig. 2 will be operated and the P lead of the first outgoing link on level 1 will be connected through over contacts $1gsh_2$ and lead 42 to contact 2 on bank OCS3 of switch OCS. Relay 2GTH in operating will effect the operation of contacts

2GTH
1GTP1—3

(not shown) and contacts

2GTH
1GTP3

will connect the second P lead on level 1 through via contacts $2gsh_2$ (not shown) to contact 3 on bank OCS3 and so on. By this means the twenty P leads on level 1 are connected through to contacts 2—21 inclusive on bank OCS3. On the operation of relay B when the control group was taken into use, contacts b_5 and b_6 will have connected up the dual testing cut-drive relay KR to wiper OCS3, and hence during the rotation of the wipers of switch OCS relay KR will be successively connected to the twenty outgoing P leads of level 1 in turn.

If the P lead connecting with contact 3 of bank OCS3 is already engaged from another group selector, wiper OCS3 will encounter an earth potential and relay KR will not operate. The switch OCS will then proceed to step on to the next position and test the second P lead and if this also proves to be busy the self-interrupted driving operation of switch OCS3 will continue until a free outlet is encountered which will be marked by an idle marking resistance battery such as that normally extended on to the incoming P leads of the group selector GSU1 and relay

KR will thereupon operate and at contacts *kr2* (Fig. 3) will open the magnet OCM driving circuit.

For the purpose of the description it will be assumed that the first of the twenty outlets on level 1 is free in which case relay KR will operate as soon as wiper OCS3 reaches position 2. Relay KR in operating at its contacts *kr1* (Fig. 4) extends earth forward over its upper low resistance winding to guard the outlet seized, and at the same time to hold itself operated. At contacts *kr2* (Fig. 3) an operating circuit is completed for relay KRR over wiper and bank OCS1 to earth via the low resistance winding of relay N. This relay in operating at contacts *krr1* and *krr2* (Fig. 1) disconnects the operating circuit for relay A, at contacts *krr3* (Fig. 4) prepares for the dual testing function of relay KR in case it should be required as will be described later, and at contacts *krr4* (Fig. 3) further disconnects the magnet OCM driving circuit. At contacts *krr5* (Fig. 4) earth is extended via wiper OCS2 in position 2 and over lead 41 to operate relay *IGSH* in the group selector, this relay corresponding to the first outlet which has been seized, while contacts *krr6* (Fig. 4) prepare to maintain relay KR operated independently of the idle marking resistance battery on the selected P lead.

Relay *IGSH* (Fig. 2) in operating in addition to operating the horizontal selecting relay *IGSP* initiates the actuation of the set of contacts

IGSP
IGSH 1—3

and at its own make-first light contacts *igsh1* (Fig. 4) completes a local locking circuit for relay KR via bank and wiper OCS4 to battery over contacts *krr6* and resistance *YHA*, while at contacts *igsh2* it extends its own operating earth through to the P lead of the outgoing link taken into use and also via contacts *igsh3* to maintain relay *IGTH* independently of the contacts *nr3*.

The calling subscriber's loop is therefore now extended through the group selector and out over the first of the twenty outgoing links on level 1 to the succeeding switch, and relays *IGTH*, *IGSH* and *IGSR* will be held from the earthed lead 41; in the meantime the control group will be proceeding to free itself in the following manner to be available for further use.

On release of relay A, contacts *a1* (Fig. 3) short-circuit relay B and this relay commences to release slowly. Before it releases an earth will have been returned over the P lead from the succeeding switch so that relays *IGSR*, (Fig. 1) *IGSH* and *IGTH* (Fig. 2) are no longer dependent for their holding on an earth supplied from the control group. On release of relay B, relays BB, KR and KRR release in turn. At contacts *b4* (Fig. 1) and *b9* (Fig. 2), the group selector prepare relays *IGSP* and *IGTP* are released but the pins or their equivalents which are engaged by the vertical bars actuated by relays *IGSH* and *IGTH* remain held. At contacts *bb3*, *kr2*, and *krr4* (Fig. 3), homing circuits are completed for switches TDS and OCS via the low resistance winding of relay N, the circuit for switch TDS extending over wiper and bank TDS1, contacts *bb3*, interrupter contacts *tdm*, magnet TDM to battery while the circuit for switch OCS is completed via bank and wiper OCS1, contacts *kr2* and *krr4*, interrupter contacts *ocm* and magnet OCM to battery. When both these switches reach their home positions, the holding circuit for relay N is opened at wipers and banks TDS1

and OCS1 and this relay proceeds to release slowly. When it does so, contacts *n2* open the holding circuit for relay NR which commences to release slowly and on the release of this relay contacts *nr1* (Fig. 1) replace the idle marking resistance battery comprising resistance *YK* and the winding of relay GS on the common test lead 31 of the control group GCG to indicate that this group is now ready to set up any further call through the associated group selector GSU1, while at contacts *nr3* the earth is removed from common lead 43, whereupon all the vertical hold relays which have been operated therefrom with the exception of relay *IGTH*, which in this instance remains held from the P lead of the seized outlet, are restored to normal.

In case the OCS switches in two or more control groups should happen to test on the same outgoing link simultaneously, then both of the KR relays will operate over their windings in series to the same idle marking resistance battery and will operate their respective relief relays KRR, while at the same time earth will be extended forward over their upper low resistance windings. In control group GCG relay KRR in operating at contacts *krr3* extends a battery potential via resistances *YL* and *YM*, and thence via contacts *b5* to energize the lower winding in opposition to the upper winding, similar remarks applying to the KR relay in the other control group.

Now in the case of a single connection from one KR relay to the outgoing P lead the opposing flux produced in the lower winding on operation of relay KRR will not be sufficient to overcome the holding flux in the low resistance upper winding and the relay will therefore hold. In the case of a dual connection the holding flux produced in each due to the current through their low resistance upper windings will be halved, while the opposing fluxes due to their lower windings will remain the same. In these circumstances both the KR relays release and cause the associated hunting switches to continue searching. Due to the difference in the speed of any two switches, after a few steps one will reach a free outlet before the other, whereupon the associated KR relay will operate to guard the outlet seized and to disconnect the magnet driving circuit.

In connection with the operation of the GTH relays when the OCS switch is about to hunt, it will be appreciated that in case a vertical internal link within the group selector GSU1 is already engaged, then it is necessary to busy the corresponding outlet on all levels of the switch. Assuming that, say, the first internal link within the switch is already engaged, then relays *IGTH* and *IGSH* will already be operated when relay 60 NR in the control group operates. Relay NR will operate the other nineteen relays 2GTH—20GTH and the switch OCS will then commence to hunt. When it reaches contact 2, since relay *IGSH* is operated in addition to relay *IGTH*, the test circuit will be broken at contacts *igsh2* (Fig. 2) so that relay KR will be unable to operate and the OCS switch will therefore proceed to advance to the next position.

If all the outlets prove to be busy, the switch 70 OCS will rotate its wipers to contacts 22 when a battery potential via resistance *YR* will be encountered by wiper OCS3 and relay KR will thereupon operate and will bring in relay KRR. Relay KRR functions as before described with the exception that contacts *krr5* (Fig. 4) now extend

earth over wiper OCS² in position 22 and then over lead 37 to operate relay INF over its left-hand winding. Relay INF in operating, at its contacts *Inf1* maintains a guarding and holding earth on the incoming P lead and at its contacts *Inf3* and *Inf4* (Fig. 1) connects itself across the incoming speaking conductors to which it locks and at contacts *Inf2* (Fig. 1) completes a locking circuit for relay GSR. At contacts *Gsr6* (Fig. 3) busy tone is connected up over common lead BTE to the centre winding of relay INF from whence it returns to the calling party. During this time the common control proceeds to release in normal manner so as to be available for use in setting up further calls in the group selector.

What we claim as new and desire to secure by Letters Patent is:

1. In a switching system, a plurality of groups of lines, a numerical switch, means for operating said switch directly to select any one of said groups, a crossbar switch thereupon operated by said numerical switch to complete connections simultaneously to all of the lines of the selected group, means for testing the lines of the selected group successively over the connections completed to the respective ones of said lines by said crossbar switch, and means operated responsive to said testing means finding a line having a predetermined condition on it for causing said crossbar switch to interrupt all of said connections except the one completed to the line having such condition on it.

2. In a switching system, a plurality of groups of lines, means for establishing a predetermined condition upon any one of said lines, a numerical switch, means for operating said switch directly to select any one of said groups, a crossbar switch thereupon operated by said numerical switch to complete a connection to each line in the selected group, and sequence means for testing each line in the selected group in turn over the connection completed to that line by said crossbar switch, thus to determine whether such line has said predetermined condition upon it.

3. In a switching system, a plurality of groups of lines, a plurality of conductors common to said groups, the different ones of said conductors corresponding respectively to the different lines in each group, impulse operated means for selecting any one of said groups, a crossbar switch thereupon operated to connect all of said conductors to the respectively corresponding lines of the selected group, and means including a hunting switch operated to connect with said conductors successively for finding an idle line in the selected group.

4. In a switching system, a crossbar switch having a plurality of groups of lines, a plurality of conductors common to said groups, the different ones of said conductors corresponding respectively to the different lines in each of said groups, impulse operated means for selecting any one of said groups and operating said crossbar switch to connect each line of the selected group to the respectively corresponding one of said conductors, testing means, and a switch operated to connect said testing means to the different ones of said

conductors at different times, thereby to determine whether the different ones of the lines in the selected group are idle or busy.

5. In a switching system, a first crossbar switch having a plurality of incoming lines, a second crossbar switch having a plurality of groups of outgoing lines, means for seizing any one of said incoming lines, means thereafter controlled by impulses over the seized line for selecting any one of said groups of outgoing lines and operating said second crossbar switch to complete connections simultaneously from all of the outgoing lines of the selected group to said first crossbar switch, means for testing each of said connections in turn, thereby to find a connection whose associated outgoing line is idle, and means operated responsive to the finding of a connection whose associated outgoing line is idle for operating said first crossbar switch to extend such connection to the seized incoming line.

6. In a switching system, a first crossbar switch having a plurality of incoming lines, a second crossbar switch having a plurality of groups of outgoing lines, means for seizing any one of said incoming lines, means thereafter controlled by impulses over the seized line for selecting any one of said groups of outgoing lines and operating said second crossbar switch to connect with the outgoing lines of the selected group, means for testing the outgoing lines in the selected group successively over the connections completed to those lines by said second switch, thereby to find an idle outgoing line in the selected group, and means operated responsive to the finding of an idle outgoing line to complete a connection from the seized incoming line to said idle outgoing line over said two crossbar switches in series.

7. In a switching system, a plurality of primary lines, a plurality of groups of secondary lines, control equipment common to said lines, means for seizing said equipment over any one of said primary lines, means in said equipment operated by impulses over said one primary line to select any one of said groups of secondary lines, a crossbar switch thereupon operated by said equipment to complete a connection to each of the secondary lines in the selected group, means for testing each of said connections in turn to determine whether the secondary line associated therewith is idle, and means controlled by said testing means responsive to finding a connection whose associated secondary line is idle for extending that particular connection to said one primary line, thereby to interconnect said one primary line with said idle secondary line in the selected group.

8. In a switching system as claimed in claim 7, equipment individual to said one primary line, and time controlled means for connecting said individual equipment to said one line and releasing said control equipment in the event that said impulses are not received within a predetermined interval of time after seizure of said control equipment.
